Garrettson Smith & Henry Brown of Philadelphia Pa.
Assignors to Wolf, Moor & Leo of Wrightsville, Pennsylvania.
Letters Patent No. 967. Dated Dec. 8th 1857.

The Schedule referred to in these Letters Patent and making part of the same

To all whom it may concern:

Be it known that we, Garrettson Smith and Henry Brown of the city and county of Philadelphia, and state of Pennsylvania, have produced a new and original Cook-Stove design, called the "National", and we do hereby declare that the following is a full, clear, and exact description thereof, reference being had to the annexed drawing forming part of this specification, in which

Figure 1, is a side elevation of the Stove.

Figure 2, is a front view of ornamental fastenings thereof, and,

Figure 3, is a front view of the foot.

Similar characters of reference in the several figures.

denote the same part.

The side of the stove bears three panels raised by mouldings A, B, C. Above the panels D, is the inscription "Patented 1857" in raised capitals and numerals. Below panels D and E, is an ornament in bas-relief made up of scrolls a, and foliage b, arranged and configured as shown in fig. 1.

Panel D is embellished in bas-relief, with foliage c, d, e, and scrolls f, g, arranged and having the configuration set forth in fig. 1. Panel E bears an ornament &c in bas-relief, made up as shown in the drawing. Panel F is ornamented with foliage h, and scroll figures, i, having the design shown in fig. 1.

The front doors II are raised above the front plate by a moulding J and each bear an ornament in bas-relief made up of foliage l, and scroll figures, m, having the configuration set forth in fig. 2. Above the doors II is the inscription "National", and number of stove in raised capitals and numerals.

The base plate K is made up upon its edge of a series of mouldings as shown in the drawings. The foot is ornamented with foliage n, and terminates in a scroll paw; the design being as fully set forth in figure 3.

I.M.P.

We claim the design, configuration and arrangement of the several ornaments in bas-relief upon the stove castings as hereinbefore described and set forth in the annexed drawing, constituting the ornamental design of cook-stove "National".
